CLAIM

The ornamental design for an electric sharpener, as shown and described.

DESCRIPTION

FIG. 1 is a top perspective view of the electric sharpener of the present invention.

FIG. 2 is a front view of the electric sharpener of the present invention.

FIG. 3 is a right side view of the electric sharpener of the present invention.

FIG. 4 is a back view of the electric sharpener of the present invention.

FIG. 5 is a left side view of the electric sharpener of the present invention.

FIG. 6 is a top view of the electric sharpener of the present invention; and,

FIG. 7 is a bottom view of the electric sharpener of the present invention.

The broken lines shown in the drawings indicate structure and features which form no part of the claimed design.
